Primary Examiner—Carol Rademaker*(74) Attorney, Agent, or Firm*—David J. Dawsey; Michael J. Gallagher; Gallagher & Dawsey(57) **CLAIM**

The ornamental design for a bottle, as shown and described.

DESCRIPTION

FIG. 1 is a front elevational view of the bottle of the claimed design, the rear elevational view being identical except for the unclaimed closure;

FIG. 2 is a top, front, left side perspective view thereof;

FIG. 3 is a right side elevational view thereof, the left side elevational being identical except for the unclaimed closure;

FIG. 4 is a top, front, right side perspective view thereof;

FIG. 5 is a bottom plan view thereof; and,

FIG. 6 is a top plan view thereof.

The broken lines in the drawing views showing a closure are included for the purpose of showing environmental structure that forms no part of the claimed design.
